UNITED STATES PATENT OFFICE

GEORGE ALBERT LYON, OF ASBURY PARK, NEW JERSEY, ASSIGNOR TO LYON INCORPORATED, OF ASBURY PARK, NEW JERSEY, A CORPORATION OF DELAWARE

DESIGN FOR A COMBINATION SPARE TIRE COVER SIDE MEMBER AND SPARE WHEEL HUB CLOSURE FOR A TIRE COVER OR SIMILAR ARTICLE

Application filed October 10, 1932. Serial No. 45,275. Term of patent 14 years.

To all whom it may concern:

Be it known that I, GEORGE ALBERT LYON, a citizen of the United States, and residing in the city of Asbury Park, in the county of Monmouth and State of New Jersey, have invented a new, original, and ornamental Design for a Combination Spare Tire Cover Side Member and Spare Wheel Hub Closure for a Tire Cover or Similar Article, of which the following is the specification, reference being had to the accompanying drawing, forming a part thereof.

In the drawing:

Figure 1 is a perspective view of my combination spare tire cover side member and spare wheel hub closure.

Figure 2 is an end view of the combina-

tion device shown in Figure 1 partly in section so as to show the contour of the outer portion of the cover side member.

These two figures clearly illustrate the novel contour of the side cover member which makes possible its use with a central wheel hub closure in such a manner as to provide the combination device with a unitary and pleasing disc-like appearance which contributes materially to the enhancing of the appearance of the spare tire and wheel cover.

I claim:

The ornamental design for a combination spare tire cover side member and spare wheel hub closure for a tire cover or similar article as shown and described.

GEORGE ALBERT LYON.
